UNITED STATES PATENT OFFICE.

CHARLES LEDIN, OF STAMFORD, CONNECTICUT, ASSIGNOR TO THE YALE & TOWNE MANUFACTURING COMPANY, OF STAMFORD, CONNECTICUT.

CYLINDER LOCK.

Application filed May 29, 1923. Serial No. 642,249.

To all whom it may concern:

Be it known that I, CHARLES LEDIN, a citizen of the United States, and a resident of Stamford, in the county of Fairfield and 5 State of Connecticut, have invented certain new and useful Improvements in Cylinder Locks; and I do hereby declare the following to be a full, clear, and exact description of the invention, such as will enable others 10 skilled in the art to which it appertains to make and use the same.

This invention relates to improvements in cylinder locks,—one object of the invention being to provide a construction whereby a 15 single spring pressed locking bar to lock the plug against rotation shall be provided and which shall be operable by a plurality of key-actuated lever-tumblers to unlock the plug from the cylinder so that said plug may 20 be turned.

With this and other objects in view, the invention consists in certain novel features of construction and combinations of parts as hereinafter set forth and pointed out in 25 the claims.

In the accompanying drawings,—

Figure 1 is a front view of a lock in which my improvements are embodied.

Figure 2 is a longitudinal sectional view 30 of the same.

Figure 3 is a view in transverse section. Figures 4, 5 and 6 are detail views.

Figure 7 is a view illustrating tumbler-lever guides, and

Figure 8 is a view showing a modification 35 of the plug.

The cylinder or casing member of the lock is represented at 1 and an elongated portion 2 of said cylinder or casing is provided with a recess 3 for a purpose herein- 40 after explained.

In the embodiment of the invention shown 45 in the drawings, the plug or rotatable member of the lock may comprise a housing member 4 provided at one end with a head 5 having a part which enters the rear end of the housing 4 and at the other end of said housing a cap or head 6 is provided and is made with a peripheral flange 7 en- 50 circling the front end of the plug housing, and said cap 6 is made with a key-slot 8. The plug member also includes a plurality of pairs of guides 9, the guides of each pair being spaced apart so as to provide a key- 55 slot for the plug and the pairs of guides are

spaced apart to receive lever-tumblers 10 between them. The caps or heads of the housing and the guides 9 and also spacers 11 are held in place by means of bolts 12 and 13 which pass through said caps or heads, 60 guides and spacers. The lever-tumblers 10 are pivotally mounted upon the bolt 12 and pressed in one direction by springs such as shown at 14, Figure 3,—each of said lever-tumblers being provided at its free end with 65 a toe 15 to engage the bolt 13 and thus limit the movement of said lever-tumblers in one direction. Each of the several lever-tumblers is provided with an upwardly projecting lug or tooth 16 and between its ends, each 70 lever-tumbler is made with a lower key-engaging edge 17 extending across the key-slot of the plug.

Instead of constructing the plug as above described it may be made in a single piece, 75 as a die casting and provided with slots for the accommodation of the tumblers, as shown in Figure 8 in which the body of the plug is shown at 18 and the slots at 19.

In the plug construction previously described and shown in Figures 2 and 3, the plug housing 4 (Figure 5) is provided with an elongated slot 20 in alignment with the recess 3 in the cylinder extension 2 and the metal of the housing at respective sides of 80 said slot is bent inwardly to provide parallel guide flanges 21. A locking block 22 enters the elongated slot 20 and normally projects partially within the recess 3 so as to normally lock the plug to the cylinder member of the lock. A follower 23 is located within the recess 3 and rests against the locking block 22. The follower is provided with sockets into which springs 24 project, the upper ends of said springs bearing 85 against the upper wall of the recess 3. The springs 24 normally press the locking block in an inward or downward direction but sufficient movement of the locking block to unlock the plug is prevented by engagement 100 of said locking block with the lugs or teeth 16 of the lever-tumblers and the engagement of the latter with the bolt 13. When a proper key is inserted into the plug it will so engage the portions 17 of the lever-tumblers as to cause pivotal movement of the latter and the lugs or teeth 16 of said tumblers to be moved out of line with the locking block, thus releasing the latter, and the spring pressed follower will operate to move 105 110

the locking block inwardly or downwardly until it engages the upper edge portions of the lever-tumblers between the lugs or teeth 16 and the free ends of said tumblers,—at 5 which time the upper or outer edge of the locking block will be in alignment with the division line between the plug and cylinder so that the plug may be rotated.

Having fully described my invention what 10 I claim as new and desire to secure by Letters-Patent, is:

1. In a cylinder lock, the combination of a cylinder member provided with an extension having a recess therein, a plug revolubly mounted in said cylinder member, a plurality of lever-tumblers mounted in said plug and projecting across the key-slot thereof, a single locking block entering said plug and the recess of the cylinder member, and spring pressure means located in said recess and engaging said locking block and normally pressing the same against the lever-tumblers.

2. In a cylinder lock, the combination 25 with a cylinder member provided with a recess, a plug revolubly mounted in said cylinder member and having a slot communicating with the recess in the cylinder member, a plurality of lever-tumblers mounted in said plug and projecting across the key-slot thereof, each of said lever-tumblers having an upwardly projecting lug, spring means for moving said tumblers in one direction, and means for limiting such 35 movement of the tumblers, of a locking block entering the slot in the plug and adapted to enter the recess in the cylinder member, and spring pressure means located in said recess and engaging said locking 40 block.

3. In a cylinder lock, the combination with a cylinder member having a recess, of a plug comprising a housing, heads at re-

spective ends of said housing and spaced guides adapted to form a key-slot, longitudinal bolts connecting said parts, spring-pressed lever-tumblers mounted on one of said bolts between the guides and limited in one direction by the other bolt, said housing member of the plug having a slot normally in line with the recess in the cylinder member, a locking block movable in said slot and normally held in locked relation to the cylinder member by the lever-tumblers, and a single spring-pressed device located in the recess in the cylinder member and engaging said locking block.

4. In a cylinder lock, the combination with a cylinder member having a recess communicating with the plug bore of said cylinder member, of a plug comprising a housing member provided with a slot and inwardly projecting guide flanges, heads at respective ends of said housing member, spaced guides within said housing member and forming a key-slot and bolts connecting said parts, of spring-pressed lever-tumblers mounted on one of said bolts and projecting across the key-slot and between the guides, the other of said bolts forming a stop for 70 said lever-tumblers and each of said lever-tumblers having an upwardly projecting lug, a locking block mounted in the slot of the plug housing and adapted to enter the recess in the cylinder member, a follower located in said recess and engaging said locking block, and spring means in said recess and engaging said follower.

In testimony whereof, I have signed this specification in the presence of two subscribing witnesses.

CHARLES LEDIN
